UNITED STATES PATENT OFFICE.

FRANCIS JERDONE, JR., OF TOLEDO, OHIO, ASSIGNOR TO THE WILLYS-OVERLAND COMPANY, OF TOLEDO, OHIO, A CORPORATION OF OHIO.

AUTOMATIC TAKE-UP DEVICE.

1,421,783.

Specification of Letters Patent. Patented July 4, 1922.

Application filed February 24, 1919. Serial No. 278,769.

To all whom it may concern:

Be it known that I, FRANCIS JERDONE, Jr., a citizen of the United States, residing at Toledo, in the county of Lucas and State 5 of Ohio, have invented certain new and useful Improvements in Automatic Take-Up Devices, of which I declare the following to be a full, clear, and exact description.

My invention relates to an automatic 10 take-up device, and has for its object to provide improved means adapted to compensate for lost motion between two or more co-operating members or mechanisms.

Another object of the invention is to provide a simple and inexpensive automatic 15 take-up device, which is particularly adapted to compensate for lost motion between the valves and cam shaft of an internal combustion engine, such as is used on motor 20 vehicles.

Another object of the invention is to provide two or more reciprocally mounted members, one of which is of tubular construction, in which is mounted means for 25 automatically effecting movement of one of said members with respect to the other to compensate for lost motion between the several parts of the mechanism.

To these and other ends the invention 30 comprises certain novel features of construction and arrangement of parts, as will be hereinafter more fully described and claimed it being understood that the invention is susceptible to certain modifications 35 not shown in the drawing, which will be comprehended by the appended claims.

A structure constituting one embodiment 40 of my invention is illustrated in the accompanying drawings forming a part of this specification, in which:

Figure I is a fragmentary-sectional elevation showing the application of my invention as applied between the valves and cam shaft of an internal combustion engine.

Figure II is an enlarged detail side elevation of the push rod shown in Figure I.

Figure III is a top plan view of same.

Figure IV is a sectional plan taken on lines IV—IV of Figure II.

Figure V is a detailed-perspective view 50 of the cam operating member shown in section in Figure I.

Figure VI is a fragmentary-sectional elevation illustrating a slightly modified 55 form of the invention.

Figure VII is a top-plan view of the push rod shown in Figure VI.

Figure VIII is a fragmentary, sectional elevation of another modification of the invention.

Figure IX is a fragmentary, sectional elevation taken on line IX—IX of Figure VIII.

Figure X is a longitudinal section 65 through the upper end of one of the push rods with the cam and cam operating parts removed.

Figure XI is an enlarged detail plan of the cam operating member shown in Figure VIII, and Figure XII is a side elevation 70 of the same.

Similar reference numerals refer to similar parts throughout the several views of the drawing.

The automatic take-up device shown and 75 described in the present application as a compensating means for lost motion between the valves and cam shaft of an internal combustion engine may readily be applied to other mechanisms where it is desired 80 to provide compensating means for lost motion between an operating and operated member or members; it being understood that the present application is merely 85 illustrative of one of the uses to which the invention may be put.

Referring to the drawings 10 represents a portion of the cylinder block or frame of an internal combustion engine, and 11 the cam shaft of the engine. The valves 12 are 90 provided with the usual valve stems 13 through the lower ends of which are extended the pins 14 for supporting the spring seats 15 carrying the lower ends of the valve closing springs 16, the upper ends of said 95 springs being held by the valve stem guides 17, which are preferably cast integral with the cylinder block. Seated upon the cams 18 of the cam shaft 11 are the heads 19 of the push rods 20, which are reciprocably 100 mounted in the guides 21 of the engine frame or block 10. The push rod 20 is provided with a longitudinally extending bore or recess 22, into which is screwed the threaded end 23 of the head 19, as shown in Figure 105 I. The upper end of the push rod 20 is provided with a transversely disposed wall 24, which is recessed to receive the cam 25, upon which is mounted the valve stem seat 26 extending into engagement with the lower end 110

of the valve stem 13. The cam 25 is preferably elliptical or spheroidal in form, and is mounted within said recessed wall with its axis extending normally at a right angle 5 to the longitudinal axis of the valve stem, it being understood that the wall 24 and seat 26 are curved to correspond with the curvature of the cam when the latter is in the position shown in Figure I. In this figure it 10 will be seen that the cam projects slightly beyond the wall 24 at one side thereof, and at this point it is engaged by the operating member 27, shown in perspective in Figure V. The operating member 27 is provided at 15 its upper end and on its inner face with a recess 28, which is curved to correspond to the curvature of the cam 25 at the end thereof. The upright portion of the cam operating member 27 normally lies in the opening 20 29 formed through the upper end wall of the push rod 20, and the horizontal portion 30 of said operating member is extended into the recess 22 of the push rod and is seated upon the upper end of a spring 31, the lower end 25 of which rests upon the extension 23 of the head 19 of the push rod. The cam operating member 27 is held upon the spring 31 and in engagement with the cam 25 by means of the guide 21 in which the push rod and operating member are slidably mounted. It 30 will be seen from this construction that the spring 31 serves to automatically move the operating member for the purpose of rotating the cam 25 to compensate for lost motion 35 between the valve and cam shaft of the engine.

In the modification shown in Figures VI and VII the parts are substantially the same as those already described with the exception 40 that the push rod 32 is made in one piece with the transverse wall 24 omitted and the bore 33 extended entirely through the upper end of the rod, the cam operating member 34 lying wholly within the bore and engaging 45 the cam at a point nearer its center than in the arrangement shown in Figure I. In this modification the annular face of the upper end of the push rod 32 is provided with a curved recess 34' as shown in Figure VII, 50 said recess being curved to correspond to the curvature of the cam 25.

In the modification shown in Figures VIII to XII inclusive, the push rod 35 is similar to the push rod 32 shown in Figure VI, with 55 the exception that it is provided at its upper end with a longitudinally extending slot or opening 36, in which the upright portion of the cam operating member 37 is mounted, the horizontal portion of said member being 60 seated upon the spring 31 in the bore 38 of the push rod, said operating member being held against lateral displacement by means of the guide or bearing 21 in which the push rod is reciprocated. The upright portion of 65 the operating member 37 where it engages

the cam is curved as indicated at 40 to correspond to the curvature of the cam 41. The cam 41 is preferably elliptical in form and is provided at its opposite sides with the trunnions 42, which are rotatably mounted 70 in curved recesses formed upon the spaced bearing portions 43 of the valve stem 13 which portions are formed by slotting or recessing the valve stem as indicated at 44 in Figures VIII and IX. In this case the 75 push rod 35 is recessed at points beneath the trunnions 42 as indicated at 45 sufficiently to prevent the contacting of the trunnions with said push rod, this construction being clearly shown in Figure IX. In this modification 80 the cam operating member 37 is actuated by the spring 31 in the bore 38 of the push rod and said operating member is guided by the push rod bearing 21, and is constantly acting upon the cam at one end thereof, tending to pivotally move the same about the cam seating point 46 on the push rod to either raise the trunnions 42 or depress the push rod to compensate for lost motion between 85 the valves and the cam shaft. 90

Having thus described my invention, what I claim as new and desire to secure by Letters Patent is:

1. In an automatic take-up device, the combination with the valve stem and push rod of an internal combustion engine, a cam shaft for actuating said parts, a cam between said valve stem and push rod, a spring carried by the push rod within a recess formed therein, and a cam operating member 95 disposed between said spring and cam for actuating the latter to compensate for lost motion between the valve and cam shaft. 100

2. In an automatic take-up device, the combination with the valve stem and push rod of an internal combustion engine, a cam shaft for operating said parts in one direction, a spring for actuating said parts in an opposite direction, a removable seat for the free end of said valve stem, a cam disposed 105 between said removable seat and the adjacent end of said push rod, a spring mounted within a recess formed in said push rod, and an operating member disposed between said spring and cam for actuating the latter to 110 automatically compensate for lost motion between the valve and cam shaft. 115

3. In an automatic take-up device, the combination with the valves and push rods of an internal combustion engine, means for 120 actuating the same, guides for said push rods and the stems of said valves, a cam mounted between each of the valve stems and push rods, a spring mounted in a recess formed in each of said push rods and an operating member for each of the cams interposed between the cam and spring and held against displacement by said push rod 125 guide. 130

4. In an automatic take-up device, the 130

- combination with the valve and valve stem of an internal combustion engine, a push rod provided with a recess, a cam seated upon the end of the push rod adjacent to the valve 5 stem and co-operating with the valve and stem to move the same, a cam operating member disposed in said recess, a spring within said recess for actuating the cam operating member, and means for actuating 10 said push rod and valve stem.
5. In an automatic take-up device, the combination with the valves and valve stems of an internal combustion engine, push rods provided with longitudinal bores and having 15 openings through their walls communicating with said bores, a cam seated upon the end of each of the push rods nearest the valve stems and co-operating with the latter to actuate the same, a spring mounted in 20 each of said bores, a cam operating member having angular portions, one of which extends into engagement with said springs and the other being disposed in the opening in 25 the wall of the push rod and co-operating with the cam to actuate the same, and means for actuating said push rods and valve stems.
6. In an automatic take-up device, the combination with the exhaust valves and valve stems of an internal combustion engine, a cam provided with trunnions rotatably engaging said valve stem, a push rod for each of said valve stems, means carried by 30 said push rod for rotating said cam upon its trunnions and pivotally moving it upon said 35 seat and means for simultaneously actuating the push rod and valve stem independently of the operation of said cam.
7. In an automatic take-up device, the combination with the exhaust valve and 40 valve stem of an internal combustion engine, a rotatable cam co-operating with the valve stem to move the same, a push rod having its end adjacent the valve stem constructed to form a seat for the cam, means carried by 45 the push rod below the cam for rotating said cam, and means for moving said push rod and valve stem in opposite directions.
8. In an automatic take-up device, the combination with two reciprocable members 50 mounted end to end, one of which is of tubular construction, means for reciprocating said members, a cam interposed between the adjacent ends of said members and means mounted in said tubular member for 55 actuating said cam to compensate for lost motion between said parts.
9. In an automatic take-up device, the combination with two or more reciprocably mounted members, one of which is of tubular 60 construction, means for actuating said members, a cam rotatably mounted between said members, a spring mounted in said tubular member, and an operating member for rotating said cam adapted to be actuated by said spring.
10. In an automatic take-up device, the combination with two or more members mounted for reciprocating movement, one of which is of tubular construction, guides for said members, means for reciprocating said 70 members within the guides, a cam rotatably mounted between said members for moving one relatively to the other, a spring in said tubular member and an operating member for the cam seated upon said spring and extending through an opening in the wall of the tubular member in sliding engagement with the guide for said tubular member. 75
11. An automatic take-up device comprising a tubular member, a spring within 80 said member, a follower arranged to be actuated by the spring and a floating cam having one end loosely engaging the wall of the tubular member and the other disposed on the follower whereby upon expansion of 85 the spring the cam will pivot about the end engaging said wall, said device being insertable between two movably mounted parts, one of which is adapted to seat upon the cam. 90
12. An automatic take-up device comprising a tubular member, a spring anchored within said tubular member, a follower arranged to be actuated by said spring, said tubular member and follower being provided with oppositely arranged concave portions and a cam having its opposite ends resting within said concave portions, the cam being adapted to pivot upon the tubular member when the follower is actuated 95 by the spring, said device being insertable between two movable parts, one of which is adapted to seat upon the cam. 100
13. An automatic take-up device comprising two relatively movable members, one of 105 which is spring actuated upon the other and a cam having its opposite ends loosely resting upon said members, said device being insertable between two movably mounted parts, one of which is adapted to be seated 110 upon the cam.
14. An automatic take-up device comprising a tubular member having a slot in the open end thereof, a spring supported within said tubular member, a follower seated upon 115 said spring having a portion disposed within said slot and extending substantially to the end of the tubular member and a cam having one end loosely resting upon the outer end of the follower and the other 120 loosely engaging the tubular member whereby when the follower is moved outwardly the cam will pivot about the end resting upon said tubular member, said device being insertable between two movable parts, one 125 of which is adapted to seat upon the cam.
- In testimony whereo I affix my signature.
